UNITED STATES PATENT OFFICE.

PAUL V. KELLEY, OF EVERETT, WASHINGTON.

FOLDING TABLE AND LUNCH-CASE FOR AUTOMOBILES.

1,378,355.

Specification of Letters Patent.

Patented May 17, 1921.

Application filed August 31, 1920. Serial No. 407,187.

To all whom it may concern:

Be it known that I, PAUL V. KELLEY, a citizen of the United States, residing at Everett, in the county of Snohomish and 5 State of Washington, have invented a new and useful Improvement in Folding Tables and Lunch-Cases for Automobiles, of which the following is a specification.

My invention relates to folding tables and 10 lunch-cases for the safe and convenient carrying of provisions and other articles for use on automobile trips with camping parties, picnics, or on tours, and has for one of its objects the construction of a table 15 that may be in daily use in the home and adapted to be quickly folded to serve as an outer casing for transporting in compact form, cooking utensils, dishes, and other essentials for cooking and serving meals.

20 My invention will be first described in the construction illustrated and its principle pointed out and the particular features thereof which are new and for which a patent is desired will then be defined by the 25 claims.

And it is hereby declared that the following description of the invention, read in connection with the accompanying drawings in which I have shown my invention in 30 the type of construction I now prefer to use, constitute a full, clear, and exact description thereof that will enable others skilled in the art to which the invention appertains to make and use the same.

35 In the drawings, similar reference characters have been employed to denote corresponding parts.

Figure 1 is a perspective view of the table and containers, shown in their relative positions for receiving edibles, cooking utensils, and other necessary articles preparatory to proceeding on a trip.

Fig. 2 is an end elevation of the device when all the separable elements are consolidated or packed on the running board 45 of an automobile for transportation.

Fig. 3 is a horizontal cross section on line $x-x$ of Fig. 2.

Fig. 4 is a horizontal cross section on line $z-z$ of Fig. 2.

Fig. 5 is a horizontal cross section on line $y-y$ of Fig. 2.

Fig. 6 is a plan view of lids 6^a , 6^a , that cover the trays 6, 6, in the inverted rectangular box frame secured to the under surface of top 4 of the table.

Fig. 7 is a perspective view of the table in position for ordinary use.

Fig. 8 is a perspective view of the device when folded and packed on the running 60 board of an automobile.

Fig. 9 is a plan view of the lid covering container 2.

The table as shown in Fig. 7 is designed to provide, when extended, a flat surface 65 36 x 42 inches, which will suffice for six persons. And in its construction I make the central portion or top 4, nine inches wide and thirty-six inches long and provide it with two leaves 3, 16 $\frac{1}{2}$ x 36 inches, that 70 are hinged to the under side of top 4 along the longitudinal edges thereof as shown at 10. Cleats 3 a are affixed to the under surface of the leaves along the transverse edges thereof to fill the space between the leaves 75 and the legs against which they rest, thereby stiffening the leaves.

The said top 4 has fixedly secured to its under surface an inverted rectangular box frame of like dimensions and to each corner 80 of said frame a leg 5 is rigidly attached; and midway between the under surface of the table top 4 and the free ends of said four legs, I fixedly secure a supplemental inverted rectangular box frame 7 of like 85 dimensions with that secured to the under surface of the top of the table.

With a table so constructed, and inverted to serve as a casing for compartments, I attain space for packing equivalent to about 90 three and one-fourth cubic feet which I apportion as follows: For edibles one and one fourth feet, and for utensils, dishes, etc., two cubic feet.

In assembling the several elements of 95 this device for the purpose of arranging for an automobile trip, the table is used as an outer casing in which everything is packed. My first move is to place everything in an accessible place, then move the 100 hinged legs of the table backward so as to enable the leaves of the table to drop; then invert the table on the running board of the car so that top 4 will be the bottom of the casing. Then place container 1 (holding cooking utensils, dishes, and the like) 105 on the bottom, which is the top of rectangular box frame secured to the under surface of the table top 4 and is provided with trays 6, 6. These trays are for use as follows: 110 One for toilet articles; and the other for knives, forks, and spoons.

I next place container 2, containing edibles, on top of supplemental rectangular box frame 7, wherein is a tray for the table linen. Bottles or flasks containing milk, condiments, and other liquids may be carried safely by packing them in upright position in containers 1 and 2. When all edibles are packed in container 2, I place the lid or cover 2^a thereon; and if all other articles to be taken on the trip are packed in their proper places I raise the table leaves 3 to vertical positions and hook them to legs 5 as shown in Fig. 8.

In choosing the dimensions for top 4 of the table I had in mind its ultimate use and purpose to which it was to be applied, that is, adapting it for resting on the running board of an automobile when the leaves are raised vertically and hooked to legs 5 as shown. The space thus occupied is 10 $\frac{3}{4}$ x 36 inches.

It will be observed that container 2 is of rectangular form and is provided on each longitudinal outer surface, at or near its diagonally opposite corners, with a rib or cleat 9 so as to retain the said container in fixed position after it has been properly placed in the folds of the table.

Container 1 is also rectangular in form and at its diagonally opposite corners is provided with shoulders or rabbets 11 to provide a recess for movable legs 8 when the table is used for an outer casing.

This device is a very convenient piece of kitchen furniture that may be transferred in a minute from kitchen use to the running board of an automobile when contemplating a trip for camping or picnic purposes, for it provides a food box 5 $\frac{1}{2}$ x 11 x 34 inches; a utensil box 9 x 11 x 33 inches, and trays for table linen, knives, forks, spoons, and toilet articles. And when the casing has been unpacked it may be inverted and a

table provided 36 x 42 inches adapted to accommodate six persons.

45

I claim as my invention—

1. In an article of the character described, a casing, in combination, composed of a folding table consisting of a top, two leaves, and six legs; four legs being rigidly attached to a rectangular box frame, and two legs hingedly secured to same frame to support the leaves, said frame being invertedly secured to the under surface of the table top and said leaves hinged to the under side of the top along its longitudinal edges, so that when the table is inverted the top thereof becomes the bottom of said casing and the leaves are adapted to be raised vertically to serve as sides of the casing; and means for securing the leaves in said vertical position, and a supplemental rectangular box frame invertedly secured between the four legs intermediate the table top and the floor.

2. In an article of the character described, a casing, in combination, composed of a folding table consisting of a top, two leaves, and six legs; four legs being rigidly attached to a rectangular box frame, and two legs hingedly secured to same frame to support the leaves, said frame being invertedly secured to the under surface of the table top and said leaves hinged to the under side of the top along its longitudinal edges, so that when the table is inverted the top thereof becomes the bottom of said casing and the leaves are adapted to be raised vertically to serve as sides of the casing; and means for securing the leaves in said vertical position, a supplemental rectangular box frame invertedly secured between the four legs intermediate the table top and the floor, and a plurality of superposed compartments within said casing.

PAUL V. KELLEY.
